UNITED STATES PATENT OFFICE.

CHARLES A. TUCKER, OF ISLIP, NEW YORK, ASSIGNOR TO THE TUCKER ELECTRICAL MANUFACTURING COMPANY, OF NEW YORK.

DESIGN FOR A PORTABLE ELECTRIC-BELL STAND.

SPECIFICATION forming part of Design No. 17,994, dated December 27, 1867.

Application filed December 30, 1885. Serial No. 187,190. Term of patent 3½ years.

To all whom it may concern:

Be it known that I, CHARLES A. TUCKER, a citizen of the United States, residing in the town of Islip, in the county of Suffolk and State of New York, have invented and produced a new and original Design for Portable Electric-Bell Stands, of which the following is a specification, reference being had to the accompanying photographs, forming a part 10 thereof.

Figure 1 is a perspective view of my design looking at the front from the left-hand corner of the same. Fig. 2 is a perspective view of the same looking at the back from the left-hand corner of the same.

Similar letters of reference indicate like parts in both the figures.

This invention relates to a new design for a portable electric-bell stand.

It consists of a base, *a*, in the form of a parallelogram, having sloping or molded sides, at the back of which base *a*, near the middle, rises a truncated pyramid, *b*, each face of which is ornamented with an outer frame or band formed coincident with the edge of the pyramid. Within this band a zigzag line passes

from the top to the bottom, and within that an oval frame having a central panel inclosed by a wreath of ivy-leaves. Above each corner of the pyramid an acorn-like ornament is placed. 30 Centrally upon the upper surface of the pyramid *b* stands a chalice, *c*, with griffins *d d* on its edge. On each side of the pyramid *b*, near the base *a*, square inkstands are supported on small stands, and on the front of the base *a*, 35 forward of and beneath the inkstands *e e*, is an elongated octagon tray, *f*, and in the center of the front of the base *a*, beneath the tray *f*, is an ornament, *g*, in the form of a pug-dog's head.

Having thus described my invention, what I claim as new, and desire to secure by Letters Patent, is—

The design for portable electric-bell stand having the following features: base *a*, truncated pyramid *b*, chalice *c*, griffins *d d*, stands *e e*, tray *f*, and ornament *g*, substantially as described and shown.

CHARLES A. TUCKER.
